RAILWAY TRAFFIC CONTROLLING APPARATUS

Filed Sept. 29, 1930

UNITED STATES PATENT OFFICE

EARL M. ALLEN, OF SWISSVALE, AND ROGER E. WILLARD, OF WILKINSBURG, PENNSYLVANIA, ASSIGNEES TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed September 29, 1930. Serial No. 485,103.

Our invention relates to railway traffic controlling apparatus, and particularly to apparatus for the control of a railway switch and the signals governing traffic over the 5 switch.

We will describe one form of apparatus embodying our invention, and will then point out the novel features thereof in claims.

The accompanying drawing is a diagrammatic view showing one form of apparatus embodying our invention.

Referring to the drawing, the apparatus in the form here shown comprises a main track A, and a branch track B connected by 15 a switch F, traffic over these tracks being normally in the directions indicated by the arrows. The main track A is divided by insulated joints 2 to form a main section D—E containing the switch F, and an approach section C—D. The branch track B is similarly provided with a main section V—Y and an approach section U—V. Each track section is provided with a track circuit comprising a track battery 3 and a track relay 20 designated by the reference character R with a distinguishing exponent.

A signal S¹, which normally indicates stop, governs traffic on the track A through the switch F; and a similar signal S², which also 30 normally indicates stop, governs traffic on branch track B through the switch F. The signal S¹ is provided with a circuit which is controlled by a front contact 12 of a normally deenergized signal relay H¹, and signal S² is similarly controlled by a front contact 31 of a normally deenergized signal relay H².

The switch F is operated by a switch mechanism M, which in turn is controlled by a 40 switch relay W as well as by others of the relays as hereinafter explained.

Located adjacent the branch track approach section U—V is a switch indicator K comprising two lamps G and R. When lamp 45 R is lighted it means that switch F cannot be reversed because there is a train on the main track A. When lamp G is lighted it means that the switch can be reversed.

Under normal conditions, that is, when the 50 apparatus is unaffected by the presence of

trains, switch F is in normal position, both signals S¹ and S² are at stop, and both lamps of the indicator K are extinguished.

We will first assume that a train moving toward the right on the main track A enters 55 the approach section C—D. This train will open track relay R¹, thereby closing the circuit for an approach relay L, which circuit is from terminal X, through back contact 4 of relay R¹, back contact 5 of a switch relay W, 60 and winding of relay L to terminal O. Signal relay H¹ will then be energized, the circuit being from terminal X, through front contact 7 of relay R², normal contact 8 of switch F, front contact 9 of relay L, front 65 contact 10 of relay R³, back contact 11 of relay H², and the winding of relay H¹ to terminal O. It will be noted that this circuit will not be closed unless the main section 70 D—E is unoccupied, switch F is in the normal position, main section V—Y is unoccupied, and signal relay H² is deenergized. The closing of relay H¹ will cause signal S¹ to give a proceed indication. When the train enters section D—E, the opening of relay R² 75 will open the circuit for relay H¹ at contact 7 so that signal S¹ will return to the stop indication.

We will now assume that a train on the branch track B enters the approach section 80 U—V, thereby opening track relay R⁴. Located adjacent this section is a normally open manually operable circuit controller T, and if this circuit controller is manually closed while the track relay R⁴ is open, a relay P 85 will become energized, the circuit being from terminal X, through back contact 13 of relay R⁴, circuit controller T, and the winding of relay P to terminal O. The circuit controller T may then be released, but relay P will remain energized as long as relay R⁴ is open, 90 by virtue of a stick circuit which passes from terminal X, through back contact 13 of relay R⁴, front contact 14 of relay P, and the winding of relay P to terminal O. Switch relay W 95 will now be energized, the circuit being from terminal X, through contact 17 of relay P, back contact 18 of relay H¹, back contact 19 of relay L, and the winding of relay W to terminal O. It will be noted that this circuit 100

cannot become closed unless relay H^1 is open so that signal S^1 indicates stop, and unless relay L is open thereby establishing that there is no train in the approach section $C-D$ of the main track A . Relay W being energized, a reverse operating circuit for the switch mechanism M will become closed, this circuit being from terminal X , through front contact 23 of relay R^2 , front contact 24 of relay R^3 , front point of contact 25 of relay W , switch operating mechanism M , and the front point of contact 26 of relay W to terminal O . It will be noted that this circuit will not be closed unless both track relays R^2 and R^3 are closed. Assuming that the switch F has become reversed, signal relay H^2 will be energized by virtue of a circuit which passes from terminal X , through front contact 27 of relay R^2 , reverse contact 28 of switch F , front contact 29 of relay R^3 , back contact 30 of relay H^1 , and the winding of relay H^2 to terminal O . Inasmuch as this circuit includes back contact 30 of relay H^1 , it follows that relay H^2 cannot become energized unless signal S^1 indicates stop. The closing of relay H^2 will cause signal S^2 to assume the proceed indication, but as soon as the train enters track section $V-Y$, this signal will return to the stop indication because of the opening 30 of the circuit for relay H^2 at contact 29. As soon as relay P becomes energized, the normal lamp R for the switch indicator K will be lighted by virtue of a circuit which passes from terminal X , through front contact 15 of relay P , back point of contact 16 of relay W , and lamp R to terminal O . When switch relay W becomes energized, the front point of contact 16 of this relay will close, thereby lighting the reverse lamp G instead of the normal lamp R , and this will indicate that the switch relay W has become energized. The subsequent clearing of signal S^2 will indicate that switch F has become reversed in response to the closing of relay W . When the train enters section $V-Y$, it will open track relay R^3 , thereby opening the switch mechanism circuit at contact 24 and so preventing the switch from being restored to its normal position. When the rear end 50 of the train leaves section $U-V$, track relay R^4 will again close, thereby releasing relay P , and this will result in opening the circuit for relay W , but as we have just stated, the circuits for switch mechanism M will now be open at front contact 24 of relay R^3 , so the switch will remain in the reverse position. As soon as the front end of the train passes point Y , track relay R^2 will become open, thereby opening at contact 23 the controlling 55 circuit for the switch mechanism M , so that the switch will remain in the reverse position until the rear end of the train passes point E . When this occurs, the normal circuit for mechanism M will become closed, this circuit 60 being from terminal X , through front con-

tact 23 of relay R^2 , front contact 24 of relay R^3 , back point of contact 26 of relay W , switch mechanism M , and the back point of contact 25 of relay W to terminal O . The switch will then be returned to its normal position so that all parts of the apparatus will be in the conditions in which they are illustrated in the drawing.

We will now assume that while a train occupies the approach section $C-D$ of the main track A , a second train enters the approach section $U-V$ of the branch track B , and a member of the train crew operates circuit controller T , thereby energizing relay P . This will not result in the reversal of switch F because the circuit for the switch relay W will be open at back contact 19 of relay L , the latter relay being energized because of the occupancy of section $C-D$. It follows that the train on the branch track B cannot receive a proceed indication from signal S^2 until the train on the main track A has passed beyond point E .

We will now assume that section $U-V$ is occupied and that a second train enters section $C-D$. If the switch relay W has not become energized when the second train enters section $C-D$, signal S^1 will assume the proceed indication because relays L and H^1 will both become energized; but if the switch relay W has been energized at the time the second train enters section $C-D$, relay L will remain deenergized, and this will prevent relay H^1 from becoming energized, and so the signal S^1 will remain in the stop position. The train on the branch track B will then have the right-of-way.

In order to simplify the drawing, we have in some instances shown relay contacts disassociated from the relays to which they belong, but have indicated the association by means of the reference characters. For example, contact 17 of relay P is illustrated at a considerable distance from the relay, but the association is indicated by the fact that the contact is designated 17^P.

Although we have herein shown and described only one form of apparatus embodying our invention, it is understood that various changes and modifications may be made therein within the scope of the appended claims without departing from the spirit and scope of our invention.

Having thus described our invention, what we claim is:

1. Railway traffic controlling apparatus comprising a main track and a branch track connected by a switch, said main track being provided with a main section containing the switch and an approach section, and said branch track being provided with an approach section, a manually operable circuit controller adjacent said branch track approach section, means requiring operation of said circuit controller coincident with oc-

cupancy of said branch track approach section to reverse said switch, and means for preventing reversal of the switch if either section of said main track is occupied.

5. Railway traffic controlling apparatus comprising a main track and a branch track connected by a switch, said main track being provided with a main section containing the switch and an approach section, and said branch track being provided with an approach section, a manually operable circuit controller adjacent said branch track approach section, means requiring operation of said circuit controller coincident with occupancy of said branch track approach section to reverse said switch, means for preventing reversal of the switch if either section of said main track is occupied, and an indicator located adjacent said branch track approach section and controlled by the switch governing means for showing the conditions of said switch.

6. Railway traffic controlling apparatus comprising a main track and a branch track connected by a switch, said main track being provided with a main section containing the switch and said branch track being provided with an approach section, a manually operable circuit controller adjacent said branch track approach section, means requiring operation of said circuit controller coincident with occupancy of said branch track approach section to reverse said switch, and means for preventing reversal of said switch if said main track section is occupied.

7. Railway traffic controlling apparatus comprising a main track and a branch track connected by a switch, said main track being provided with a main section containing the switch and an approach section, and said branch track being provided with an approach section, a manually operable circuit controller adjacent said branch track approach section, means requiring operation of said circuit controller coincident with occupancy of said branch track approach section to reverse said switch, means for preventing reversal of the switch if either section of said main track is occupied, a normal danger signal for the main section of said main track, and means for clearing said signal when a train occupies said main track approach section provided the main section of the main track is unoccupied and the switch is normal and said circuit controller has not been operated even though a train may be occupying said branch track approach section.

8. Railway traffic controlling apparatus comprising a main track and a branch track connected by a switch, said main track being provided with a main section containing the switch and an approach section, and said branch track being provided with an approach section, a manually operable circuit controller adjacent said branch track ap-

proach section, means requiring operation of said circuit controller coincident with occupancy of said branch track approach section to reverse said switch, a normal danger signal for said main section of the main track, means for clearing said signal when a train occupies said main track approach section provided the main section of the main track is unoccupied and the switch is normal and said circuit controller has not been operated even though a train may be occupying said branch track approach section, a normal danger signal for said branch track, and means for clearing the latter signal provided said switch is reversed and said main section of the main track is unoccupied and said main track signal indicates stop.

9. Railway traffic controlling apparatus comprising a main track and a branch track connected by a switch, an approach section for said branch track, a track circuit including a track relay for said approach section, a normally open manually operable circuit controller adjacent said approach section, a normally open relay P, a pick-up circuit for relay P closed only when said circuit controller is closed and said track relay is open, a stick circuit for relay P closed when relay P is closed and said track relay is open, and means for reversing said switch to permit a train to enter the main track from the branch track when relay P is closed provided there is no train on the main track approaching the switch.

10. Railway traffic controlling apparatus comprising a main track and a branch track connected by a switch, an approach section for said branch track, a track circuit including a track relay for said approach section, a normally open manually operable circuit controller adjacent said approach section, a normally open relay P, a pick-up circuit for relay P closed only when said circuit controller is closed and said track relay is open, a stick circuit for relay P closed when relay P is closed and said track relay is open, a normally open switch controlling relay W which when energized causes the switch to be reversed to permit a train to enter the main track from the branch track, and means for energizing said relay W when relay P is energized provided there is no train on the main track approaching the switch.

11. Railway traffic controlling apparatus comprising a main track and a branch track connected by a switch, an approach section for said branch track, a track circuit including a track relay for said approach section, a normally open manually operable circuit controller adjacent said approach section, a normally open relay P, a pick-up circuit for relay P closed only when said circuit controller is closed and said track relay is open, a stick circuit for relay P closed when relay P is closed and said track relay is open, a 125

normally open switch controlling relay W which when energized causes the switch to be reversed to permit a train to enter the main track from the branch track, means for energizing relay W when relay P is energized provided there is no train on the main track approaching the switch, and a switch indicator located adjacent said approach section and controlled jointly by said relays P and W.

9. Railway traffic controlling apparatus comprising a main track and a branch track connected by a switch, an approach section for said branch track, a track circuit including a track relay for said approach section, a normally open manually operable circuit controller adjacent said approach section, a normally open relay P, a pick-up circuit for relay P closed only when said circuit controller is closed and said track relay is open, a stick circuit for relay P closed when relay P is closed and said track relay is open, a normally open switch controlling relay W which when energized causes the switch to be reversed to permit a train to enter the main track from the branch track, means for energizing relay W when relay P is energized provided there is no train on the main track approaching the switch, a switch indicator located adjacent said approach section and having a normal and a reverse lamp, a circuit for said normal lamp including a front contact of relay P and a back contact of relay W, and a circuit for said reverse lamp including a front contact of relay P and a front contact of relay W.

In testimony whereof we affix our signatures.

EARL M. ALLEN.
